Primary Examiner — Mojtaba Tehrani(57) **CLAIM**

The ornamental design for a solar powered animal repellent, as shown and described.

DESCRIPTION

FIG. 1 is a rear, left and top perspective view of a solar powered animal repellent showing my new design; FIG. 2 is a front, right and bottom perspective view thereof; FIG. 3 is a rear view thereof; FIG. 4 is a front view thereof; FIG. 5 is a right side view thereof; FIG. 6 is a left side view thereof; FIG. 7 is an enlarged top view thereof; and, FIG. 8 is an enlarged bottom view thereof. The broken lines depict portions of the solar powered animal repellent that form no part of the claimed design.
